UNITED STATES PATENT OFFICE

HAROLD G. SABIN, OF NEW HAVEN, CONNECTICUT

DIGGER-BUCKET CONTROL

Application filed May 3, 1929. Serial No. 360,154.

This invention relates to improvement in digger-bucket controls and while primarily designed as a toy is applicable for use in diggers for practical purposes, the object being to provide means for controlling the movement of the bucket so that by means of a single lever the bucket may be held stationary, allowed to run free, or upon the further movement of the lever to arrest one of the control-ropes, so that the bucket will open, and the invention consists in the construction as hereinafter described and particularly recited in the claims.

In illustrating my invention, I have shown it in connection with a toy of the "tractor" type, but this is immaterial as the invention may be used in connection with a boom or a crane.

In the accompanying drawings:

Fig. 1 is a side view illustrating a form of digger-bucket control embodying my invention;

Fig. 2 is a top or plan view thereof;

Fig. 3 is a side view of the bucket-control mechanism on an enlarged scale;

Fig. 4 is a front view thereof;

Fig. 5 is a perspective view of the control lever detached;

Fig. 6 is a perspective view of the operating-ratchet and crank detached; and

Fig. 7 is a front view of the portion of the buckets showing the connection of the ropes therewith.

In carrying out my invention, I employ a main shaft 10 provided with a crank 11 by which it may be turned, and secured to the shaft are the two ends of a rope 12, the reaches 13 of which are each given a turn around a secondary shaft 14 parallel with the shaft 10, the said reaches being arranged on opposite sides of flanges 15 and 16, so as to provide space between them for a rope 17, which is fastened to the shaft 14.

From the shaft 14 the reaches 13 pass over the idlers 18 and 19 on a shaft 20 which is mounted in the outer end of a boom 23, thence downward through a yoke 24, and thence downward through a weight 25 on a shaft 26 to which buckets 27 and 28 are pivoted, the said buckets being connected with

the shaft 26 and with the yoke 24 by links 29 and 30, in the usual manner of "clam-shell" buckets.

The rope 17 passes over an idler 31 between the idlers 18 and 19 and downward into connection with the center of the yoke 24 and between the reaches 13.

On the shaft 10 is a ratchet 32, and engaging with this ratchet is a pawl 33 formed as part of a lever 34 which is normally held in engagement with the ratchet by a spring 35. The lever 34 extends beyond the shaft 14 and is formed with a notch 36 to engage with that shaft and preferably the surface of the notch will be serrated so as to allow the lever to frictionally engage with said shaft so as to arrest the movement thereof.

In a construction employing the boom 23 an additional shaft 37 will be employed provided with a crank 38 by which it may be turned, and fixed to this shaft is a rope 39 extending over an idler 40 and thence to the outer end of the boom, whereby the boom may be raised or lowered.

When it is desired to raise the bucket, the crank 11 is turned and this crank turns the shaft 10 and winds the rope 12 thereon, and as the ends of the rope are wound on the shaft 10 they turn the shaft 14 and wind the rope 17 thereon, the pawl 33, engaging the ratchet 32, holds the rope 12 in any position of adjustment, and as the reaches are separated and held separate by the yoke 24, the bucket will not rotate.

To allow the bucket to lower, the lever 34 will be moved so as to lift the pawl 33 out of engagement with the ratchet 32, thus freeing the shaft 10 and allowing the bucket to drop. To open the bucket, however, the lever will be further advanced so as to engage with the shaft 14 and arrest the running of the rope 17 and hence stop the movement of the yoke 24. This permits the weight 25 to continue downward and open the buckets 27 and 28. If the shaft 14 is then released, the buckets in their open position will continue to go down until the movement of the shaft 10 is arrested.

It will thus be noted that the action of the lever 34 is to permit the shafts 10 and 14 to

be turned, then moved to release the shaft 10 and finally moved to hold the shaft 14.

While I have shown a "clam-shell" bucket, it is obvious that the invention may be used in the so-called "orange-peel" type of bucket, and it is obvious without further illustration that instead of employing the boom, my control-mechanism might be mounted in an overhead crane or carriage.

10 I thus not only produce a very attractive toy which can be operated without having the ropes of the buckets twist but I also have devised practical means for controlling the operation of buckets for practical purposes.

15 I claim:

1. A bucket-control comprising two shafts, a rope having its ends attached to one shaft and given a turn around the other shaft, another rope fixed to said second shaft, said 20 ropes extending into connection with a bucket, a ratchet fixed on the first shaft, and a pivotal lever provided with a pawl adapted to engage said ratchet and formed with a notch to engage with the second shaft.

25 2. A bucket-control comprising two shafts, a rope having its ends attached to one shaft and given a turn around the other shaft, another rope fixed to said second shaft, said 30 ropes extending into connection with a bucket, a ratchet fixed on the first shaft, and a spring-actuated pivotal lever provided with a pawl adapted to engage said ratchet and formed with a notch to engage with the second shaft.

35 3. A bucket-control comprising a main shaft with means for moving the same, a secondary shaft parallel with the first shaft, flanges mounted on said secondary shaft, a rope, the ends of which are secured to the 40 first shaft and turned about the second shaft outside the flanges, whereby the movement of the rope will turn said second shaft, a rope fixed to said second shaft between said flanges, idlers over which said ropes pass, the said 45 ropes having separate connection with a bucket-mechanism, a ratchet connected with said first shaft, a lever provided with a pawl to engage with said ratchet, and a spring tending to hold the pawl in engagement with 50 said ratchet, said lever extending beyond the second shaft and formed with a friction-surface to engage therewith and so designed that the lever normally holds the first shaft against 55 rotating in one direction, the first movement of the lever releasing the first shaft without engaging the second shaft, leaving both shafts free, and further movement of the lever engaging the second shaft to arrest the movement thereof.

60 In testimony whereof, I have signed this specification.

HAROLD G. SABIN.
